INVENTOR

BY Thomas F. Hallad
ATTORNEY

UNITED STATES PATENT OFFICE

137,832

DESIGN FOR A JACKET OR SIMILAR ARTICLE

Lillian Raphael, New York, N. Y.

Application February 21, 1944, Serial No. 112,658

Term of patent 14 years

(Cl. D3—4)

To all whom it may concern:

Be it known that I, Lillian Raphael, a citizen of the United States of America, residing in New York city, county of Kings, and State of New York, have invented a new, original, and ornamental Design for a Jacket or Similar Article, of which the following is a specification, reference being had to the accompanying drawing, forming part thereof, wherein,

Figure 1 is a front view of a jacket or similar article showing my new design, and,

I claim:

The ornamental design for a jacket or similar article, substantially as shown.

LILLIAN RAPHAEL.
